D11-148.

OR D7,428

EX

JOSEPH W. FISKE, OF NEW YORK, N. Y.

DESIGN FOR ORNAMENTAL VASE.

Specification forming part of Design No. 7,428, dated May 12, 1874; application filed April 21, 1874.
[Term of Patent 7 years.]

JOSEPH W. FISKE.

Witnesses:

JOHN H. BIRD,
B. F. BLAIR.

UNITED STATES PATENT OFFICE.

JOSEPH W. FISKE, OF NEW YORK, N. Y.

DESIGN FOR ORNAMENTAL VASE.

Specification forming part of Design No. 7,428, dated May 12, 1874; application filed April 21, 1874.
[Term of Patent 7 years.]

J.

To all whom it may concern:

Be it known that I, J. W. FISKE, of New York, in the county of New York and State of New York, have invented certain Improvements in Design for an Ornamental Vase, of which the following is a specification:

This is a design for an ornamental vase, the nature of which is fully shown in the accompanying photographic illustration.

The bowl consists of two parts, B and C, the lower part B being a shallow oval basin, with its upper part curved inward and reduced in diameter where it is united to the part C, and being ornamented on its under exterior surface by figures of leaves in relief. The upper portion C is curved outward, and terminates in a broad overhanging border, which is scalloped on its edge, and ornamented on its upper surface, as shown. A handle, D, is attached to the bowl on its two opposite sides, the upper portion of the handle being connected to the upper part C of the bowl, and the lower portion of the handle to the lower part B of the bowl. The bowl is supported on a body, A, which is grooved or fluted vertically, smallest at its center, where it is surrounded by a small fillet or molding, from whence it curves rapidly outward both above and below, terminating above in an annular scalloped or beaded projection, above which is an annular molding composed of three members of gradually decreasing diameter, upon which the bowl rests. At the bottom the body A terminates in a rectangular base, to which it is united by an oval or convex molding, ornamented on its exterior surface, all as shown in the photograph.

What I claim as my invention is—

The design for a vase, substantially as shown and described.

JOSEPH W. FISKE.

Witnesses:

JOHN H. BIRD,
B. F. BLAIR.